D 11,961

No. 11,961

August 31, 1880

UNITED STATES PATENT OFFICE.

LEWIS F. GRISWOLD, OF MERIDEN, CONNECTICUT, ASSIGNOR TO THE CHARLES PARKER COMPANY, OF SAME PLACE.

DESIGN FOR SPOONS AND FORKS.

SPECIFICATION forming part of Design No. 11,961, dated August 31, 1880.

Application filed July 27, 1880. Term of patent 14 years.

To all whom it may concern:

Be it known that I, LEWIS F. GRISWOLD, a citizen of the United States, residing at Meriden, in the county of New Haven and State of Connecticut, have invented a certain new and useful Design for Spoons and Forks; and I do hereby declare the following to be a full, clear, and exact description of the said design, reference being had to the accompanying drawing, and to letters or figures of reference marked thereon, which forms a part of this specification.

The accompanying drawing represents a front view of the handle of a fork or spoon constructed and ornamented in accordance with my design, hereinafter described.

The chief features of the said design are, first, an outline for the handle, consisting of straight sides terminating in an open fan; and, secondly, an arrangement of figures representing a bamboo rod, a bird, and marsh-plants known as "cat-tails" upon the front of said handle.

In the aforesaid drawing, A designates the shank of a fork or spoon, and B the handle thereof. At the point where the said parts A and B meet there is on the spoon a nearly circular raised rim, a, which apparently serves to contain the base or roots of a clump of cat-tail plants, C, delineated in raised figures upon the front of the handle B and extending toward its rear end. Perched on one of the upper sprays of the clump is a bird, D, having his wings spread, as if just alighting. There is a bamboo rod, E, extending obliquely across and along the front of the said handle, beginning near the said bird and ending where it is apparently overlapped by a terminal outspread

fan, F. All the foregoing figures, except said fan, are entirely contained within the straight 40 tapering sides b b of said handle. These sides are provided with a raised rim, which is in continuation of rim a, the latter being open at the top to leave room for the cat-tail stalks, and then caused to extend upward and backward 45 in gradually-diverging lines. The lower or handle part of fan F is, of course, within these lines, but the broad upper part extends beyond the rest of the spoon-handle at the rear end and at the rear corners thereof. The said fan 50 may be ornamented in divers ways, and a curved line, b', is preferably formed thereon, to appear as though the rear end of the spoon-handle showed through the slats.

The figures above described may be marked 55 on the spoon-handle or fork-handle, or sunken into the same in any way; but raised figures are preferable.

Having thus fully described my invention, what I claim as new, and desire to secure by 60 Letters Patent, is—

1. A design for a spoon-handle or fork-handle, consisting of straight tapering sides and a terminal fan, arranged substantially as set forth. 65
2. A design for a spoon-handle or fork-handle, consisting of a bamboo stalk, a bird, and a marsh plant or plants of the kind known as "cat-tails," all arranged substantially as set forth. 70

In testimony whereof I affix my signature in presence of two witnesses.

LEWIS F. GRISWOLD.
